UNITED STATES PATENT OFFICE.

PHILIP H. APPLE, OF LAVALLE, WISCONSIN.

SCRUBBING-MACHINE.

No. 870,335.

Specification of Letters Patent.

Patented Nov. 5, 1907.

Application filed April 26, 1907. Serial No. 370,421.

To all whom it may concern:

Be it known that I, PHILIP H. APPLE, a citizen of the United States, residing at LaValle, in the county of Sauk and State of Wisconsin, have invented certain new and useful Improvements in Scrubbing-Machines, of which the following is a specification.

This invention relates to floor scrubbing machines.

One object is to provide a portable machine for scrubbing floors or other places through the instrumentality of rotary brushes.

Another object resides in the provision of a scrubbing machine embodying such characteristics that its brush heads will be supplied with water carried by the machine, the water being supplied in regulated quantities.

Another object of the invention is to produce a machine of this character embodying flexibly arranged brush supporting devices whereby the brushes remain in contact with the floor at all times during the operation of the device.

In the drawings: Figure 1 is a transverse sectional view of the invention. Fig. 2 is a longitudinal sectional view. Fig. 3 is an enlarged detail sectional view illustrating one of the brush head shaft mountings. Fig. 4 is a top plan view of the handle frame.

Referring now more particularly to the accompanying drawings, the reference character 1 indicates a casing having a drive shaft 2 journaled through its ends for the support of the carrier wheels 3, the shafts having spaced beveled gears 4 and 5 keyed thereupon for a purpose presently explained.

Disposed within the casing 1 is a hanger 6 having upturned ends engaging the shaft 2 and bearing against the inner faces of the ends of the casing and provided with perforations in its bight or body portion in which are rotatably mounted the short vertical sleeves 12 which receive short shafts 7 and 8 secured upon the brush heads by the socket plates 11 and held in perfect vertical position by means of the sleeves 12 as best shown in Figs. 1 & 3. These short shafts 7 and 8 have vertical movement in their corresponding sleeves, but are held against rotation within the sleeves by virtue of a pin *b* carried by each of said short shafts and projecting through the vertical slot of the corresponding sleeve, as shown in Figs. 1 and 3.

Mounted upon the upper ends of the sleeves 12 are beveled pinions 13 and 14, for mesh with the aforesaid gears 4 and 5, respectively, to rotate the brushes when the machine is moved across the floor or other place. The brushes are yieldably supported by means of helical or other springs 15 encircling the sleeves 12 and bearing at their upper ends against the bosses *a* depending from the body of said hanger 6 and at their lower ends against the socket plates 11.

Mounted upon the top of the casing is a water reservoir 17 having communication with a spout 18 leading

into the casing 1 and terminating immediately over the space between the brushes 9 and 10. The opening between the reservoir 17 and its spout 18 is controlled by a valve 19 operated by an operating handle 20 extending through the casing and provided with a knob 21 exteriorly of the casing, whereby the water may be delivered to the brushes or to the floor in regulated quantities.

Secured to the ends of the casing 1 are the side handle brackets 22 each braced by a brace 23 and connected at their free ends by a cross bar 24 intermediate the ends of which latter is formed a socket 25 for the detachable reception of the inner end of the handle 26, there being a key 27 piercing the socket 25 and the inner end of the handle 26, whereby it may be secured properly in place. Slidably disposed upon the handle 26 is a slide 28 carrying a spring snap 29 to hold cloth for the purpose of wiping up the floor when the handle is detached from its socket. When the handle 26 is in its socket the slide 28 is preferably near the outer end of the handle and not near the inner end thereof until it is desired to use the handle for mopping purposes. The slide 28 may be held in its different positions upon the handle 26 by means of a set screw 30.

Brackets 31 are secured to the ends of the casing 1 for the support of the rear wheels 32 of the machine, the brackets 31 being connected by an axle 33 upon which said wheels 32 are mounted.

From the foregoing it will be understood that the brush heads 9 and 10 are yieldably supported whereby they may readily ride over uneven surfaces, and also permit the casing 1 to be moved to a limited extent without disturbing the position of the brushes, or removing them from their operative contact with the floor and by reason of the gear and pinion arrangement herein as described the brush heads are designed to rotate in opposite directions, and it will also be understood that while the machine is provided with a running gear including front and rear wheels, the front wheels provide the driving power for the machine.

What is claimed is:—

A machine of the class described comprising a casing, a drive shaft mounted for rotation through said casing and having bearing wheels, gears spaced apart upon said shaft within said casing, a hanger disposed within said casing and having upturned ends swinging upon said shaft and bearing against the inner faces of the casing, short vertical shafts mounted for rotation in said hanger and with brushes at one end and gears at their other ends meshing with the gears of said drive shaft, and a handle rigidly connected to said casing.

In testimony whereof I affix my signature, in presence of two witnesses.

PHILIP H. APPLE.

Witnesses:

EDY POERSTIK,

R. E. PADDICK.
